UNITED STATES PATENT OFFICE.

JAMES E. JACKSON, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR FINISHING INSOLES.

1,162,721.

Specification of Letters Patent. Patented Nov. 30, 1915.

Application filed September 18, 1911, Serial No. 650,020. Renewed March 5, 1914. Serial No. 822,767.

To all whom it may concern:

Be it known that I, JAMES E. JACKSON, a citizen of the United States, and resident of Lynn, in the county of Essex and State of Massachusetts, have invented certain new and useful Improvements in Machines for Finishing Insoles, of which the following is a specification.

The present invention relates to machines for preparing insoles of the Gem type; that is to say, insoles whose edges are slit to form lips which are turned up to receive stitches, each sole being covered with reinforcing material, such as canvas, on the side from which the lip stands up. A perfect insole of this type must have the reinforcing material pressed thoroughly into the angles at the junction of the lip with the sole, otherwise the stitches by which the upper is attached to the insole will be loose and will permit the upper to pull away from the insole so as to expose the stitches. This looseness of the reinforcing material is a common fault, although attempts have been made to provide machines which will press the reinforcing material snugly about the lip and into the angles.

The present invention provides a machine adapted to press the reinforcing material into the angles and to stretch the material tightly over the upper surface of the sole and over the lip so as to overcome the defect explained. This operation is known commercially as "rib tightening" and "lip hardening."

This invention embodies a number of improved structural features one of which is a jaw carrier on which is mounted a pair of jaws adapted to grip the lip of the insole and move bodily to feed the insole step by step.

Another feature is a work support adapted to coöperate with the inner lip-engaging jaw to compress the sole behind the lip so as to reduce the thickness of the sole at that point as nearly as possible to the thickness of the margin of the sole outside the lip. The advantage derived from thus compressing the sole occurs when the shoe is undergoing a sewing operation in a machine for attaching the upper to the insole with or without a welt. The curved needle of such

a machine enters the lip from the outside and emerges at the inner side, the point of the needle being generally caused to enter the lip at its junction with the margin of the sole. The margin of the sole is considerably thinner than that part of the sole lying within the lip, because of the stock which is taken away from the margin to form the lip. Consequently, when the needle passes through the lip it meets a greater thickness of stock behind the lip and oftentimes passes considerably beyond the lip before emerging from the sole. Now, therefore, if the sole be compressed at its junction with the inner side of the lip, the needle will more readily emerge at the said junction after passing through the lip, so that all the stitches upon being drawn tight will lie in the angle at the inner side of the lip.

Other features of the invention are illustrated upon the accompanying drawings and hereinafter explained and claimed.

On the drawings, which illustrate one form in which the invention may be embodied: Figure 1 represents a side elevation of the machine. Fig. 2 represents a front elevation of the machine. Fig. 3 represents an elevation, partly in section, of the feed jaws in open position, and the adjacent parts. Fig. 4 represents a rear elevation of the mechanism included in Fig. 3. Fig. 5 represents a side elevation of a lever for changing the length of feed, the elevation being the reverse of that represented by Fig. 1. Fig. 6 represents a top plan view of the lever shown by Fig. 5, and includes other parts in section. Fig. 7 represents a perspective view of a swinging carrier upon which the feed jaws are mounted. Fig. 8 represents an elevation of the lower end of the inner feed jaw. Fig. 9 represents an elevation of the lower end of the outer feed jaw. Fig. 10 represents a portion of an insole before being subjected to the action of the jaws, as shown by Figs. 8 and 9. Fig. 11 represents a section similar to Fig. 10, showing the results of the operation of the jaws.

The same reference characters indicate the same parts wherever they occur.

On the drawings the machine is illustrated as having a base 10 and a working head or

frame 11 provided with suitable bearings for a main power shaft 12. A work support is indicated at 13, and the rib-tightening and feed jaws are indicated at 14 and 15 respectively, the jaw 14, hereinafter termed the outer jaw, being adapted to engage the outer face of the lip and the feather or marginal extension of an insole *a*, while the jaw 15 is adapted to engage the inner face of the lip and the surface of the sole inclosed by the lip. One of the jaws is movable relatively to the other for gripping the lip, and both jaws are movable in unison for feeding the sole step by step.

As shown by Fig. 7, the jaw 15 which engages the inner side of the lip is carried at the lower end of a carrier 16. The jaw is rigid with relation to the carrier, and in the present instance is an integral part thereof. The upper end of the carrier is bored for the reception of the main shaft 12, whereby the carrier is adapted to swing as a pendulum about the shaft to impart feeding movement to the jaws. The movable jaw 14 is pivotally connected to the carrier by a pivot stud 17, the location of the pivot with relation to the work-engaging faces of the jaw being of especial importance, as hereinafter explained. The jaw 14 is connected by a link 18 with a plunger 19 fitted to slide in bearings in the carrier. A spring 20 connected to the plunger and to the carrier tends to raise the plunger to open the jaw. The jaw is closed positively by a cam 21 on the shaft 12, the upper end of the plunger 19 being provided with an adjustable abutment 22 for engagement with the cam, said abutment being shown in the form of a setscrew.

Swinging movement is imparted to the carrier to feed the work by an arm 23 affixed upon a rock shaft 24. The free end of the arm 23 is connected with the carrier by a link 25. An arm 26, also affixed to the rock shaft 24, is arranged to be engaged by a cam 27 on the main shaft. The arm 26 is held against the cam by a leaf spring 28, the action of the cam effecting the feeding movement, and the action of the spring effecting the return movement of the carrier.

When the machine is operating upon the toe of an insole where the curve is very sharp, it is desirable to shorten the length of the feeding steps, and for this reason the machine is provided with a device for that purpose. This device is shown by Figs. 1, 5 and 6 and comprises an arm 29 having a shoulder 30. The arm 29 is carried by the lever 26, being connected thereto by a pivot 31. The cam surface 30 co-operates with a pin or projection 32 (see Fig. 6) projecting from the frame 11. A spring 33 tends to keep the arm 29 raised, and a rod 34 extends downwardly from the free end of the arm 29 and may be provided with a treadle (not

shown). When the feed cam 27 imparts a feeding movement, the lever 26, together with the arm 29, is moved away from the projection 32, and when the lever 26 is returned by its spring 28 the length of the return movement is determined by the position of the arm 29, the arm 29 in its upper position being adapted to permit maximum return movement; but when in its lower position, the shoulder engages the projection 32 and cuts short the return movement. The shoulder 30 is preferably beveled, as shown by Fig. 6, so as to avoid positive resistance to downward movement of the arm 29 in case the arm should be depressed while lying against the projection 32. When the return movement of the lever 26 is thus limited, a portion of the throw of the feed cam is wasted and the carrier 16 receives a comparatively short movement.

A presser-foot 35 is provided for engaging the marginal portion of the sole outside the lip to clamp the sole against the support 13 during the return movement of the feed jaws. The presser-foot is affixed to the lower end of a plunger 36, which plunger extends through a sleeve 37 hereinafter described. It may be here stated, however, that the movement of the plunger 36 is wholly independent of the sleeve 37. An arm 38 is affixed to the upper end of the plunger 36, said arm being provided with a rod 39 which extends downwardly. (See Fig. 1.) The lower end of the rod 39 is adapted to be engaged by a lever 40, which lever is pivoted at 41 and adapted to be operated by a cam 42 on the shaft 12. The presser-foot is normally held downwardly upon the work support by a spring 43 (see Fig. 2), and is positively raised by the cam 42. The rear end of the lever 40 extends beyond the cam 42 and is connected to a rod 44 which extends downwardly to a treadle (not shown) whereby the presser-foot may be manually raised.

As hereinbefore stated, this invention comprises means for compressing the sole behind the lip to reduce the thickness of the sole at that point as nearly as possible to the thickness of the margin outside the lip. This compressing operation is effected by causing relative movement of the work support and the inner feed jaw 15 in such manner as to indent the sole a small portion at a time. The word "indent" as herein used does not imply the well-known operation of indenting the stitches by which an outer sole is attached, but means the compressing of a small portion of the insole at one time and repeating the operation at a series of points to form, as it were, a groove in the insole wherein the thickness of the leather is reduced. So far as the result is material, either of these elements may be moved toward and from the other. In the present in-

stance, the work support is moved toward the feed jaw to compress the sole, thus utilizing the shaft 12 as an abutment for resisting the upward pressure of the work support.

Referring to Fig. 1, the work support is provided with a cylindric stem 45. This stem is arranged in a socket formed in a boss 46, the lower end of the stem 45 bearing upon the upper end of a plunger 47. The plunger extends downwardly through the base 10 and is provided with a collar 48 and surrounded by a spring 49 which normally tends to depress the plunger. A pin 50 affixed to the upper end of the plunger extends outwardly through a slot 51 in the boss 46. (See Figs. 3 and 4.) The pin also extends through a slot 52 in a member 53 which is affixed to the lower end of the sleeve 37 hereinbefore mentioned. The sleeve is mounted to slide vertically in bearings formed in the frame 11. An arm 54 affixed to the upper end of the sleeve carries a hardened member 55 which engages a cam 56 on the shaft 12. The effects of the cam are to lift the sleeve and thereby lift the work support to press the insole against the jaw 15. The hardened member 55 is adapted to be adjusted to render the compressing movement positive, or to be otherwise adjusted to render the compressing movement yielding. For this purpose the hardened member is provided with a screw-threaded stem 57 which extends through the arm 54 and is provided with check nuts 58. A hollow spring 59 contained in a socket in the arm 54 exerts its tension upon the member 55 to press said member toward the cam. In order to render the action of the cam positive, the check nuts 58 are turned to draw the member 55 tightly against the arm 54, thus eliminating the spring 59 as an active element. In order to render the action yielding the check nuts 58 are unscrewed to permit the member 55 to move downwardly with relation to the arm 54. In addition to this change of adjustment, the arm 54 is raised slightly with relation to the sleeve 37. This latter adjustment is effected by loosening the setscrew 60 by which the arm 54 is affixed to the sleeve. When the arm 54 has been raised with relation to the sleeve and the member 55 has been released so as to be subject to the tension of the spring 59, the upward movement of the work support is made yielding.

The member 53 is connected with the pin 50 by a manually operative latch 61. (See Fig. 4.) The latch is provided for holding the work support in operative position, but may be moved to release the work support so that the latter may drop to facilitate the insertion and removal of the work. The latch is pivotally mounted upon the member

53 by a pivot member 62. A finger 63 formed on the latch has a cam surface 64, and a slight depression 65 for the reception of the pin 50 when the latch is in working position, as shown by Fig. 4. At the completion of the operation the latch may be moved manually, being provided with a handle for that purpose, to withdraw the finger 63 from under the pin 50. The spring plunger 47 is thereby released so that it 75 may descend and so that the work support may descend with it. When a new piece of work is placed upon the work support it may be raised to operative position by depressing the handle of the latch, thus causing the cam surface 64 to engage and raise the pin 50. The latch is held in operative position not only by its weight but by the pin 50 resting in the notch 65.

Referring now to Figs. 1, 8 and 9, the faces 14^a and 15^a of the feed jaws are formed to stand at an inclination to the surface of the work support when the jaws are in gripping position. This arrangement of the gripping faces bends and sets the lip 90 of the sole inwardly and facilitates the beating out operation, to which the shoe is subsequently subjected, and the folding in of the lip, as well as having other advantages well known to those skilled in the art.

The face 14^a of the jaw 14 is adapted to engage the feather or marginal portion of the sole outside the lip, but does not engage such marginal portion until after compression by the inner jaw, because of the reduced thickness of the marginal portion. It will be observed that the pivot 17 about which the jaw 14 swings is so located as to cause both of the faces 14^a and 14^b to recede from the lip and margin respectively when the jaw is opened. In view of this action it is seen that on the reverse movement the two faces engage the reinforcing fabric where it is unsecured, as shown in Fig. 10, before the jaw 14 is finally seated in the outside angle, 110 and in its final inward movement the jaw draws the fabric inwardly from the edge of the sole toward the lip to the position shown in Fig. 11.

The face 15^a at the lower end of the jaw 15 is the face which co-operates with the work support to compress the sole behind the lip. It will be observed that this face is inclined with relation to the surface of the work support, the faces 15^a and 15^b forming an acute angle. By reason of inclining the face 15^a in this manner, the greatest compression of the sole occurs at the junction of the inner side of the lip with the sole. There are two advantages in compressing the sole in this 120 manner: First, the face 15^a acts as a cam or wedge to draw the sole laterally so that the point of the jaw will find its way into the crease or angle where the lip joins the sole. In this way the canvas or other reinforcing 130

material which extends over the lip and over the sole becomes slightly stretched and tightly forced into the crease. To those skilled in the art it is well known that the reinforcing material is coated with adhesive material so as to cause it to stick to the sole. Second, the advantage of compressing the sole against the inclined face 15^a is to reduce the thickness of the sole most at the point where the greatest reduction is needed in order to facilitate the passage of the needle through the lip. The curved line 66 in Fig. 11 represents the curvature of a needle such as that used in a machine for sewing 15 the upper to the insole.

The stem 45 of the work support is free to turn in the boss 46, and the work support is therefore adapted to rotate as the work is fed, thereby facilitating the feeding 20 operation. After an insole has been placed in operative position it is not necessary to guide it while the machine is in motion, the feed jaws being adapted to turn the work little by little as it advances, because the 25 lip of the insole remains always between the jaws. As a result of the operation of the jaw 14 on the reinforcing material, the edge thereof is drawn back slightly from the edge of the insole, as shown by Fig. 11, so that 30 the reinforcing material will not be visible when the insole is attached to an upper.

It will be recognized by those skilled in the art, from the foregoing description, that certain features of the invention are not 35 limited to use in a machine for operating on reinforced insoles.

Having thus explained the nature of my 40 said invention and described a way of constructing and using the same, although without attempting to set forth all the forms 45 in which it may be made or all the modes of its use, what I claim is:

1. In a machine for preparing insoles, a 45 pressure member having a relatively broad work-engaging surface upon which a sole may be fed, a coöperative pressure member having a relatively limited surface for compressing the sole at its junction with the lip, said limited surface member being 50 adapted to follow the inner side of the lip and remain in contact therewith, and means for vibrating one of said members with sufficient force to reduce the thickness of the 55 sole.

2. In a machine for preparing insoles, coöperative work-engaging members one of 60 which has a relatively limited sole-engaging surface at an angle to the plane of the sole, and means for causing said members to indent an insole behind the lip.

3. In a machine for preparing insoles, a 65 pair of jaws adapted to grip the lip of an insole, said jaws being movable laterally for feeding the insole, and means for compressing the insole against the jaw upon the inner

side of the lip, whereby the thickness of the sole upon the inner side of the lip is reduced.

4. In a machine for preparing insoles, compressing means adapted to reduce the thickness of an insole behind the lip thereof, and a feeding member adapted to engage the outer side of the lip to grip the lip against the compressing means, said lip-engaging member and said compressing means being movable for gripping the lip and movable for feeding the insole.

5. In a machine for preparing insoles, a compressing member adapted to engage the smooth side of an insole, a combined compressing and feeding member having a face adapted to engage the opposite side of the insole behind the lip thereof, and a face adapted to engage the inner side of the lip, means for causing relative compressing movement of said members toward each other sufficient to reduce the thickness of the sole, a feeding member adapted to engage the outer side of the lip, means for causing relative gripping movement of said feeding members, and means for causing feeding movement of said feeding members.

6. In a machine for preparing insoles, a member having a surface for compressing an insole at its junction with the inner side 95 of the lip, a member having a surface of relatively large area for engaging the reverse side of the sole opposite said compressing surface, one of said members being movable toward and from the other, and means for closing said members with sufficient force to reduce the thickness of the sole.

7. In a machine for preparing insloes, means for feeding an insole, coöperative work-engaging members one of which has a relatively limited sole-engaging surface, and means for forcing one of said members intermittently toward the other for indenting a series of small portions of the sole behind the lip, whereby the thickness of the sole 110 behind the lip is reduced.

8. In a machine for preparing insoles, a pair of jaws for gripping the lip of an insole, a carrier for said jaws, said carrier being adapted to impart feeding movement to said jaws, one of said jaws being affixed to said carrier and adapted to engage the inner side of the lip, the other jaw being relatively movable for gripping, and means 115 adapted to coöperate with said fixed jaw for compressing the sole behind said lip.

9. In a machine for preparing insoles, a pair of jaws for gripping the lip of an insole, a carrier for said jaws, said carrier being adapted to impart feeding movement to said jaws, one of said jaws being affixed to said carrier and adapted to engage the inner side of the lip, the other jaw being relatively movable for gripping, and means 125 130

adapted to coöperate with said fixed jaw for compressing the sole behind said lip, the sole-compressing face of said fixed jaw being inclined to the direction of compression, 5 whereby the greatest compression will be at the junction of the lip and sole.

10. In a machine for preparing insoles, a pair of jaws for gripping the lip of an insole, the inner jaw having a sole-engaging face at an acute angle to the lip-engaging face, said jaws being movable for feeding the sole, and means for coöperating with the sole-engaging face of the inner jaw to indent the sole behind the lip.

15. 11. In a machine for preparing insoles, means for feeding an insole step by step, a work support for engaging the flat side of the sole, an indenting member for engaging the opposite side of the sole behind the lip, 20 the indenting face of said indenting member being at an angle to the confronting face of the work support, and means for moving one of said members toward and from the other to indent the sole step by step.

25. 12. In a machine for preparing insoles, a pair of jaws for gripping the lip of an insole, a work support, said support and the inner jaw being capable of relative movement, and means for causing such relative 30 movement to indent the sole behind the lip, the sole-engaging face of said inner jaw being inclined to that of the support so as to indent most deeply at the junction of the lip and sole, the lip-engaging faces of said 35 jaws being inclined to said table for bending the lip inwardly, said jaws being movable for feeding the sole.

40. 13. In a machine for preparing insoles, a movable work-support, a pair of jaws for gripping the lip of an insole, said jaws being movable for feeding the work, and means for moving said work support toward said jaws with force sufficient to cause indentation of the sole by one of said jaws.

45. 14. In a machine for preparing insoles, a movable work support, a pair of jaws for gripping the lip of an insole, said jaws being movable for feeding the work, and means for moving said work support toward said 50 jaws to compress the sole, said means being capable of adjustment for rendering its compressing movement either positive or yielding.

55. 15. In a machine for preparing insoles, a pair of jaws adapted to engage the lip of an insole, said jaws being relatively movable for gripping and movable for feeding, the work-engaging portion of the outer jaw being movable at an angle to both the lip and 60 the sole.

65. 16. In a machine for preparing insoles, a pair of jaws for gripping the lip of an insole, a carrier for said jaws, said carrier being movable for imparting feeding movement to the jaws, means for reciprocating

said carrier, and spring-tensioned means adapted to be manually displaced for varying the length of feeding movements.

17. In a machine for preparing insoles, a pair of feed jaws adapted to grip the lip 70 of an insole, said jaws being mounted upon a pivot about which they are movable for feeding, and means movable radially with relation to said pivot for compressing the sole against one of said jaws.

18. In a machine for preparing insoles, a member for indenting an insole behind the lip, a reciprocatory member for pressing the work against said indenting member, yielding means for retracting said reciprocatory member, and means for moving said reciprocatory member to cause indentation, said means having a manually operative member adapted to be disconnected to release said reciprocatory member.

19. In a machine for preparing insoles, a pair of jaws adapted to grip the lip of an insole, said jaws being movable laterally for feeding the insole, a work support movable toward and from the jaws, and means for moving said work support toward said jaws to compress the insole, said means including manually operative connections whereby said work support may be moved to and locked in operative position.

20. In a machine for preparing insoles, a pair of jaws adapted to grip the lip of an insole, said jaws being movable laterally for feeding the insole, a work support movable toward and from the jaws, and reciprocatory means for moving said work support toward said jaws to compress the insole, said means including manually operative mechanism for connecting and disconnecting said work support so that it may be retracted from the jaws for insertion and removal of the insole.

21. In a machine for preparing insoles, a work support, means for feeding the work, a presser-foot adapted to coöperate with the 110 work support to clamp the work, said work support and presser-foot being movable toward and from each other, a sleeve and a rod therein, means for reciprocating said sleeve, and means for reciprocating the rod, 115 one of said reciprocatory members being connected to the work support, and the other being connected to the presser-foot for the purpose specified.

22. In a machine for preparing insoles, a 120 member for indenting an insole behind the lip, a reciprocatory member for pressing the work against said indenting member, yielding means for retracting said reciprocatory member, and means adapted to be connected to said reciprocatory member for moving the same to cause indentation, said means having a manually operative member adapted to move said reciprocatory member toward the indenting member and to maintain oper- 125

ative connection with the reciprocatory member.

23. In a machine for preparing reinforced insoles, a pair of jaws adapted to grip the lip of an insole, a member for engaging the opposite side of the insole to compress the sole against the inner jaw, means for causing relative movement of said inner jaw and said member for compressing the sole, and 10 means for closing said jaws while the sole is compressed, whereby the reinforcing material is drawn inwardly from the edge of the sole toward the lip.

24. A machine for preparing insoles, having, in combination, an inside lip compressing jaw, an oscillatory outside lip compressing jaw, a jaw actuator, and a link connecting the outside jaw to the actuator, whereby on movement of said actuator the 20 jaws are caused to engage and compress both sides of the lip.

25. A machine for preparing insoles, having, in combination, a sole support, an inside lip engaging jaw, an oscillatory outside lip 25 engaging jaw, said jaws having complementary lip engaging faces inclined to said sole support, a jaw actuator, and a link connecting the outside jaw to the actuator, whereby on movement of said actuator the 30 jaws are caused to engage and bend the lip inwardly.

26. A machine for preparing insoles, having, in combination, means for supporting and feeding the insole and for operating on 35 its lip including a pair of jaws one at each side of the lip, one of said jaws being pivotally mounted for swinging movement relatively to the other, a jaw actuator movable relatively to said pivotally mounted jaw, 40 cam means for operating said actuator, and means connecting said actuator and jaw, whereby the jaws are caused to engage and press upon both sides of the lip.

27. A machine for preparing reinforced 45 insoles, having a layer for reinforcing fabric on each side of the lip and across the feather, having, in combination, an inside lip preparing tool having an acting portion adapted to enter the vertex of the angle 50 at the inner side of the lip, a vibratory outside lip preparing tool having an acting portion to enter the vertex of the angle at the outer side of the lip, means for intermittently causing the inside tool to enter said in- 55 side angle to tighten the fabric, and means for causing said outside tool to move inwardly into the said outside angle to compress the lip against the inside tool and draw the reinforcing fabric inwardly across the 60 feather and toward the lip.

28. A machine for preparing insoles, having, in combination, an inside lip preparing tool having an inclined face to engage the inner face of the lip, an oscillatory outside 65 lip preparing tool having an inclined face

to engage the outer face of the lip, and means for causing the lip to be engaged by said tools and bent inwardly between said inclined faces.

29. A machine for preparing reinforced 70 insoles, having a layer of reinforcing fabric on each side of the lip and across the feather, having, in combination, an inside lip preparing tool having an inclined face to engage the inner face of the lip, an oscillatory 75 outside lip preparing tool having an angular portion to enter the vertex of the angle at the outside of the lip forming an inclined face to engage the outer face of the lip and a face to engage the feather, and means for 80 vibrating said outside tool across the feather to press the reinforcing fabric inwardly into said angle and against the feather and bend the lip inwardly between said inclined faces of said tools.

30. A machine for preparing reinforced insoles, having, in combination, a jaw carrier, a pair of jaws mounted thereon adapted to enter the two angles at the sides of the lip, actuating means sustained by said carrier to relatively move said jaws to grip and press the reinforcing fabric into said angles and secure it to the insole, and means for moving said jaw carrier in the line of feed while the lip is gripped to feed the 95 insole.

31. A machine for preparing insoles, having, in combination, a sole support, a jaw carrier above said support mounted for oscillation in the line of feed about an axis 100 transverse to the line of feed, a pair of jaws mounted on said carrier arranged to engage and compress the lip from each side, and means to oscillate said jaw carrier while the lip is gripped to feed the insole.

32. A machine for preparing insoles, having, in combination, a sole support, a jaw carrier above said support mounted for oscillation in the line of feed about an axis 110 transverse to the line of feed, a pair of jaws mounted on said carrier arranged to engage and compress the lip from each side, a driving shaft arranged transverse to the line of feed, an actuator on said driving shaft, and operative connections between said actuator and jaw carrier to oscillate the latter while the lip is gripped to feed the insole.

33. A machine for preparing reinforced insoles having a layer of reinforcing fabric on each side of the lip and across the feather, 120 having, in combination, a sole support, a jaw shaped to project into the vertex of the angle at the inner side of the lip, and to engage said inner side, a second jaw shaped to engage the entire surface of the outer side 125 of the lip and the feather, means for relatively moving said jaws in a direction to engage and press the reinforcing fabric on the lip, and means for relatively moving the jaws and sole support to press the rein- 130

forcing fabric on the sole at each side of the lip.

34. A machine for preparing insoles, having, in combination, a compressing jaw at the inner side of the lip, a second compressing jaw at the outer side of the lip, and means for relatively closing said jaws on the lip operating to impart a combined downward and inward movement, and means for

moving said jaws in the line of feed while closed on the lip to feed the insole.

In testimony whereof I have affixed my signature, in presence of two witnesses.

JAMES E. JACKSON.

P. W. PEZZETTI.

Copies of this patent may be obtained for five cents each, by addressing the "Commissioner of Patents, Washington, D. C."

It is hereby certified that in Letters Patent No. 1,162,721, granted November 30, 1915, upon the application of James E. Jackson, of Lynn, Massachusetts, for an improvement in "Machines for Finishing Insoles," errors appear in the printed specification requiring correction as follows: Page 4, line 104, claim 7, for the word "insloes" read *insoles*; page 6, line 45, claim 27, for the word "for" read *of*; same page, line 91, claim 30, after the word "grip" insert the words *the lip*; and that the said Letters Patent should be read with these corrections therein that the same may conform to the record of the case in the Patent Office.

Signed and sealed this 25th day of January, A. D., 1916.

[SEAL.]

R. F. WHITEHEAD,

Acting Commissioner of Patents.

Cl. 12—20.
